UNITED STATES PATENT OFFICE.

GEORGE HITE BECKWITH, OF CHARLESTOWN, WEST VIRGINIA.

REMEDY FOR HOG-CHOLERA.

SPECIFICATION forming part of Letters Patent No. 361,741, dated April 26, 1887.

Application filed July 16, 1886. Serial No. 208,196. (No specimens.)

To all whom it may concern:

Be it known that I, GEORGE HITE BECKWITH, of Charlestown, in the county of Jefferson and State of West Virginia, have invented a new Specific for Hog-Cholera, of which the following is a specification.

As the result of experiment and observation for several years in the treatment of hog-cholera, I have discovered a medicinal remedy for that disease which has proved to be efficacious in the great majority of the many cases in which it has been administered. It is composed of mandrake, sulphur, carbonate soda, charred coffee, and chlorate of potash, in equal, or nearly equal, proportions by weight. These are reduced to powder and intimately mixed.

The part of the mandrake (or may-apple) I employ is the root. The soda is conveniently found in the form of the ordinary bicarbonate commonly sold and used. The coffee, either in the form of the berry or as a coarse powder, is burned until it assumes a black or very dark shade.

The mixture or compound is obviously strongly alkaline and adapted to act on or stimulate the liver, which I have found to be an indispensable quality in all remedies for hog-cholera.

The remedy is administered most conveniently by mixing it with liquid food—such as bran slop or kitchen slop. Take one-half gallon of the latter and add one hundred grains of the above mixture. This constitutes a dose for a swine of full, or nearly full, growth, and should be administered every second day until the disease shall disappear. I also strongly

recommend the addition of one tea-spoonful of pure spirits of turpentine to the above quantity of slop. Tar should likewise be applied to the inside of the feeding-trough twice a week.

This remedy is equally valuable as a prophylactic. As such its administration should be begun in the early part of summer and sometimes in early spring, when the days are warm and dry. It may be given as often as above directed. Brood-sows may take it from four to six weeks after bearing. It should be given once a week to hogs that are being fattened for slaughter.

To define more fully the novelty of my compound, I will state that mandrake and sulphur and the alkali known as "sal-soda" have been employed for the cure of hog-cholera, in conjunction with lime, garget, saltpeter, copperas, and ginger. This compound is, however, intended to and will act very differently from mine. In brief, its composition indicates that the fecal discharges are to be checked by counteracting agents—viz., astringents—whereas my compound acts chiefly upon the liver and is not astringent, or but slightly so.

What I claim is—

The improved remedy for hog-cholera, which is composed of mandrake, sulphur, bicarbonate of soda, charred coffee, and chlorate of potash, in equal proportions, as specified.

GEORGE HITE BECKWITH.

Witnesses:

FRANK BECKWITH,
OLIN BEALL.
